[57] CLAIM

The ornamental design for a coin-operated game machine for retrieving prizes, as shown and described.

DESCRIPTION

FIG. 1 is a front and right side perspective view of a coin-operated game machine for retrieving prizes showing my new design;

FIG. 2 is a top plan view thereof;

FIG. 3 is a front view thereof;

FIG. 4 is a right side view thereof;

FIG. 5 is a rear view thereof;

FIG. 6 is a left side view thereof;

FIG. 7 is a bottom plan view thereof;

FIG. 8 is a front and side perspective view of a second embodiment of the coin-operated game machine for retrieving prizes as disclosed in FIG. 1;

FIG. 9 is a top plan view of FIG. 8;

FIG. 10 is a front view of FIG. 8;

FIG. 11 is a right side view of FIG. 8;

FIG. 12 is a rear view of FIG. 8;

FIG. 13 is a left side view of FIG. 8; and,

FIG. 14 is a bottom plan view of FIG. 8.
